VAPOR ELECTRIC DISCHARGE DEVICE

Filed April 15, 1930

Inventor:
Christian Kramer,
by *Charles E. Muller*
His Attorney.

UNITED STATES PATENT OFFICE

1,920,753

VAPOR ELECTRIC DISCHARGE DEVICE

Christian Krämer, Berlin-Pankow, Germany, assignor to General Electric Company, a Corporation of New York

Application April 15, 1930, Serial No. 444,568, and in Germany July 24, 1929

4 Claims. (Cl. 250—27.5)

My invention relates to electric discharge devices, such as mercury arc rectifiers or the like, and has for its principal object the provision of an improved means for reducing the number of back-ignitions produced in such rectifiers during operation.

High power rectifiers are sometimes provided with one, and sometimes with several suction apertures in order to remove residual gases evolved in the course of operation. A good vacuum may be thus obtained, but back-ignitions are frequently produced because the stream of mercury vapor rising from the cathode prevents, in certain circumstances, the residual gases from rising and being removed from the vicinity of the anodes.

The number of back ignitions is greatly reduced by the present invention, according to which the container of the rectifier is divided by a cowl into two concentric chambers which are separately exhausted.

My invention will be better understood from the following description when considered in connection with the accompanying drawing, and its scope will be pointed out in the appended claims.

Referring to the drawing, the single figure illustrates a mercury arc rectifier constructed in accordance with my invention.

Referring to the drawing, the container *g* of the rectifier is closed by an upper cover *d* traversed in the usual way by the leads of the anodes *a*. A water-cooled cowl *h* is fitted to the centre of the said upper cover of the rectifier, the upper portion of the cowl leading to a vacuum pump *p*₁ through the suction pipe *s*₁. The chamber which concentrically surrounds the cowl *h* and in which the anodes are located, is in communication with another suction pipe *s*₂ connected to a second vacuum pump *p*₂. When the rectifier is under high load, the bulk of the rising stream of mercury vapor from the cathode *k* is intercepted by the cowl *h*; the mercury condenses and the residual gases thus released flow to the suction pipe *s*₁. The stream of mercury vapor produces a comparatively high pressure in this chamber; this pressure has however no detrimental effect upon the anodes and in certain circumstances may even assist, due to its pumping action, the removal of gases therefrom. The pressure in the outer anode chamber is therefore lower than in the cowl.

The residual gases flowing from the anode-protecting cylinders are removed by the vacuum pump *p*₂ through the suction pipe *s*₂.

The main stream of vapor flows without eddies from the cathode, into the cowl, so that the residual gases may leave the anode-protecting cylinder unimpeded through the lower portion thereof. A further advantage consists in that the high density of vapor produced at the cathode cannot spread and as a result a low density of vapor, free from extraneous gases and improving the operation of the rectifier, may be maintained in the anode chamber.

The hollow water-cooled cowl may be replaced by a solid cowl of sheet-metal the inner and outer faces of which may be used as supports for cooling coils.

What I claim as new and desire to secure by Letters Patent of the United States is:

1. An electric discharge device including a container, an anode supported by a wall of said container, a cowl supported by said wall and dividing said container into two concentric chambers separate from each other at the upper portions thereof, two separate evacuating means to exhaust said chambers separately, one of said evacuating means opening into said cowl at a point therein in the upper portion thereof, the other of said evacuating means opening into said container at a point therein outside said cowl and in the upper portion of the outer of said concentric chambers.

2. An electric discharge device including a container, a cowl supported by a wall of said container and dividing said container into two concentric chambers separate from each other at the upper portion of said container, an anode supported on said wall between said cowl and another wall of said container, and two separate evacuating means to exhaust said chambers separately, said two evacuating means opening respectively into said cowl in the upper portion thereof and into the upper portion of the space constituting the outer of said concentric chambers between said cowl and said other wall.

3. An electric discharge device including a container, a cowl supported by a wall of said container and dividing said container into two concentric chambers separate from each other at the upper portion of said container, an anode sup-

ported on said wall between said cowl and another wall of said container, two separate evacuating means to exhaust said chambers separately, said two evacuating means opening respectively into said cowl in the upper portion thereof and into the upper portion of the space constituting the outer of said concentric chambers between said cowl and said other wall, and means for circulating a cooling medium in contact with the wall of said cowl.

4. An electric discharge device including a container, a cowl supported by a wall of said container and dividing said container into two con-

centric chambers separate from each other at the upper portion of said container, an anode supported on said wall between said cowl and another wall of said container, two separate evacuating means to exhaust said chambers separately, said two evacuating means opening respectively into said cowl in the upper portion thereof and into the upper portion of the space constituting the outer of said concentric chambers between said cowl and said other wall, and means for cooling said cowl.
